Application August 2, 1945, Serial No. 608,490

7 Claims. (Cl. 250—27.5)

1

The present invention relates to electron discharge devices and more particularly to vacuum tubes specially designed to operate at ultra-high frequencies and having greatly increased power capacity at the upper end of the frequency region. More specifically, the invention pertains to a construction and an assembly technique, including the treatment of parts, which results in the fabrication of a tube of the aforesaid type characterized by simplicity of construction, ruggedness and improved electrical characteristics.

It is an object of the present invention to provide an ultra-high frequency, high-power vacuum tube of the triode, concentric cylindrical type which is particularly adapted for incorporation, as an amplifier or as an oscillator, in a grounded grid circuit, commonly known as a grid separation circuit, which includes a resonant cavity between the anode and grid, a resonant cavity between the grid and cathode, and shielded co-axial coupling lines or other forms of coupling between the cavities.

Another object of the invention is to provide a tube of the type mentioned which, when used in a circuit of the kind above identified, is capable of functioning, for example, as an oscillator at frequencies ranging between at least 500 and 1000 megacycles with an available power output, at the upper end of this range, of the order of at least 10 to 25 watts, while the tube is operating substantially continuously (as distinguished from pulse operation).

Another object is the provision of a tube structure in which the electron transit time is substantially reduced by close spacing obtained between the cathode and the grid, and by designing the cathode to increase the current density therefrom.

Another object of the invention is to provide a construction in which the tube elements may be accurately and solidly mounted, thus avoiding misalignment or disalignment, respectively, of said elements, which may occur in the initial assembly of the parts or because of changes in temperature of the tube in use.

A further object is to provide a tube structure in which the electrode assemblies minimize the effect of inductance at ultra-high frequencies by having the electrode elements concentrically and co-axially arranged.

A still further object of the invention is the provision of a vacuum tube construction, adapted for ultra-high frequencies, composed of sub-assemblies which are fabricated into main assemblies by a technique which permits all of the

internal metal parts to be cleaned before mounting within the tube, whereby unclean metal surfaces are avoided which produce high resistance at operating frequencies with consequent tube losses resulting in inefficient operation.

A special object is to provide a tube structure in which the final seals are made glass-to-glass, thus avoiding the danger of disalignment of metal parts which may be caused through sealing.

In order to provide a tube having the structural and electrical characteristics stated above, the various electrodes of the tube must be spaced close to each other and must be properly aligned and supported with sufficient rigidity to prevent short circuiting due, for instance, to unequal expansion of the various elements of the tube or to electrodynamic forces developed between the various elements. Because of the technical requirements, such as those indicated above, considerable difficulties would ordinarily be encountered in constructing a tube having the desired electrical characteristics, and, because of these requirements and difficulties, such tubes would usually have to be custom-made. However, the structure and mode of handling the several component parts of the tube, as contemplated by this invention, not only assure adequate construction and provide the desired electrical characteristics but so facilitate the manufacture of the tube that it can readily be produced on mass-production basis. Particularly, the construction of the tubes as provided by this invention, makes it possible to manufacture the individual parts in quantities for stock storage, to assemble such parts into units, assemble such units into main sections, and finally assemble such sections to complete the tubes.

Other objects and advantages of the invention will be apparent from the following detailed description, based upon the accompanying drawings, in which:

Fig. 1 is a perspective view of an electron discharge tube constructed in accordance with the invention;

Fig. 2 is an enlarged longitudinal cross-sectional view taken substantially on line 2—2 in Fig. 1;

Fig. 3 is a transversal cross-sectional view looking generally in the direction of arrows 3—3 in Fig. 2;

Fig. 4 is a transversal cross-sectional view looking in the general direction of arrows 4—4 in Fig. 2;

Fig. 5 is an exploded view showing, in section and on an enlarged scale, the particular con-

struction of the parts forming the anode and grid-ring unit;

Fig. 6 is an exploded view showing, partly in elevation and partly in section, the preferred construction of the parts forming the grid unit;

Fig. 7 is an exploded view showing the assembled anode and grid-ring unit in section and the assembled grid unit partly in elevation and partly in section, and illustrating the preferred mode of connecting said units together to form the anode-grid assembly section;

Fig. 8 illustrates, in section, the particular construction of the parts forming the cathode base unit and the mode of assembling the same;

Fig. 9 illustrates the preferred mode of sealing the heater rod to the cathode base unit;

Fig. 10 is an exploded view illustrating the mode of assembling the heater and heat baffle means with the heater rod of the cathode-base unit;

Fig. 11 is a longitudinal cross-sectional view showing the completed cathode assembly section;

Fig. 12 is a perspective view of a device particularly adapted for use with the improved tube to air-cool the same;

Fig. 13 is an enlarged cross-sectional detail illustrating the cooperative association of the tube with the device shown in Fig. 12;

Fig. 14 is a perspective view of a device particularly adapted for use with the improved tube to water-cool the same; and

Fig. 15 is an enlarged cross-sectional detail illustrating the cooperative association of the tube with the device shown in Fig. 14.

TUBE STRUCTURE

As hereinbefore indicated and as will more clearly appear from Fig. 1, the tube, generally designated by the reference character 20, is particularly adapted for cooperative association with concentric co-axial lines or other cavity resonator circuits of the grid separation type. Thus, the physical embodiment of the tube is such that it can become, in fact, an integral part of the complete electrical system and provide therefor a walled-off and evacuated section to house the electronic activity. Accordingly, the tube 20 preferably has a substantially cylindrical configuration and includes exposed disk-like anode, grid, and cathode connections 21, 22 and 23 respectively, which are arranged in spaced superposed relationship, the space between the anode and grid connections being sealed by a cylindrical envelope 24 and the space between the grid and cathode connections being sealed by a cylindrical envelope 25.

Also, as hereinbefore indicated, the tube 20 is especially devised to operate substantially continuously at ultra-high frequencies with relatively high-power outputs. This is best attained, in accordance with the present invention, by providing, as more clearly seen in Figs. 2 and 3, a cathode 26, a grid 27 and an anode 28 respectively arranged in concentric and co-axial relationship.

The cathode 26 is particularly constructed to have the same high frequency potential throughout, and is adapted to produce by electron emission relatively high current density. It is preferably made short and wide (its effective length being less than its diameter). It essentially comprises an inverted cup-shaped body having a substantial thickness to insure uniform heat distribution. A coating 29 (Fig. 3), of suitable material is applied on the outer peripheral surface of the cathode to assure the proper emission of electrons.

The cup-shaped cathode 26 is supported in position by means of a tubular thermal insulator 30 of metal which, in turn, is carried by a cylindrical re-entrant portion 31 of a base member 32 which forms the cathode connection 23. It is to be noted that the opposite end portions of the thermal insulator 30 respectively overlap a substantial portion of the cathode 26 and of the re-entrant portion 31, the latter having a shoulder 33 in abutting engagement with said thermal insulator so that mechanical rigidity and accurate alignment of the cathode assembly is readily achieved without use of a supporting wire frame structure or the like, or without dielectric supports.

The re-entrant portion 31 terminates with a reduced neck section 34 cooperating with a seal 35 to support a centrally disposed heater connector rod 36 extending into the cup-shaped cathode 26 and projecting outwardly of the tube through the said re-entrant portion. That section of the rod 36 which projects outwardly of the tube is preferably partially enclosed in a tubular connector member 37 snugly fitted within and securely fixed, as by brazing as shown at 38, to the base re-entrant portion 31, whereas that section of the rod 36 which extends within the cup-shaped cathode 26 carries a coil-shaped heater element 39 provided with a depending extension 40 fixedly connected, for instance as shown at 41, to the reduced neck portion 34 of said base re-entrant portion 31. Disposed on the rod 36 between the heater element 39 and seal 35, is a heat-baffle structure preferably consisting of a pair of spaced flanged disks 42 interconnected by means of rods 43 and having apertures 44 to accommodate the heater connecting extension 40 without allowing electrical contact between the extension 40 and the said discs 42. The baffle disks 42 may conveniently be insulated from the rod 36 by means of ceramic inserts 45 retained in position by means of a spacer rod 46 welded or otherwise suitably affixed to the said rod 36.

The grid 27 is particularly constructed for minimum high frequency losses and uniform transit time in all parts of the tube. It is preferably of the "squirrel-cage" type and comprises a circular grid-cap 47, an annular grid-support 48 and a plurality of closely spaced grid-wire elements 49 rigidly secured to said grid-cap and grid-support. The grid-wire elements 49 are supported in parallel relation to the axis of the cathode 26 and are formed to extend in close proximity to the effective or electron emitting surface of the latter, the spacing between the cathode and the grid being of the magnitude of ten mils. Reinforcing connector or tie rods 50 are preferably provided at widely spaced points between the grid-cap 47 and grid-support 48 to add to the rigidity of the grid structure. In order to add further to the rigidity of the grid structure and also to facilitate mounting, the grid-support 48 is constructed with a rigid outwardly and downwardly flaring skirt and is provided with an annular lateral flange 51 for the attachment of said grid structure to a grid-ring 52 which forms the grid-connection 22. The grid structure is attached to the grid-ring 52 preferably by means of screw-threaded elements 53 passing through openings 54 (see Figs. 6 and 7) in the grid support flange 51 for engagement with screw-threaded apertures 55 in said grid-ring (see Fig. 7).

The anode 28 is particularly devised to obtain the desired amplification factor with the particular type of grid described above, while maintaining a good ratio of G_m to grid-plate capaci-

tance. Moreover, since the anode must dissipate relatively high wattage and since its area is relatively small in keeping with the overall dimensions of the tube (which in accordance with one embodiment, has an overall length of approximately $3\frac{1}{4}$ " and an overall diameter of approximately $1\frac{3}{8}$ "'), the anode is particularly devised to be effectively air or water cooled in the manner to be hereinafter described. The anode 28, therefore, is constructed to be wholly exposed outside the tube and to form a part of the envelope. It is provided with an inset or well portion 56 and an annular lateral flange portion 57 offset from said well portion 56 to constitute the anode connection 21. The provision of such well and offset portions permits proper concentric alignment of the anode body with the grid 27 and cathode 26 and affords sufficient spacing between the anode and grid connections for effective association with the resonant cavity circuit. An aperture 58 is provided in the top surface of the anode for evacuating the tube, which aperture may be adequately closed, after evacuation, by sealing an exhaust tubulation 59.

From the foregoing description, it will be appreciated that the particular constructional features of the tube make it possible to standardize the several parts forming such a tube and that, therefore, the parts may be manufactured in quantities for stock storage to be subsequently assembled and processed in assembly line techniques. The preferred mode of assembling and processing the parts will now be described.

In accordance with the invention and as will clearly appear from Figs. 5 through 11, the parts are first assembled into units which are then assembled into main sections, these main sections being finally assembled to complete the tube. While there is no particular order in which the units and main sections must be manufactured and assembled, the following sequence is adopted for convenience in describing the mode of manufacturing the tube.

ANODE-GRID ASSEMBLY SECTION

Anode-grid-ring unit

In Fig. 5 there are shown the several parts which constitute the anode-grid-ring unit, said parts including the exhaust tubulation 59, the anode 28, a tubing section 24a which forms the cylindrical envelope 24 between the anode and grid connections (Figs. 1 and 2), the grid-ring 52, and a tubing section 25a which forms a portion of the envelope 25 between the grid and cathode connections 22 and 23 (Figs. 1 and 2). The anode and grid-ring are made of suitable metal, such as the alloy commonly known under the trade name of "Kovar," and the exhaust tubulation and tubing sections are preferably made of glass suited for use with that kind of metal. Glass known as "Corning-7052" has been found suitable for the purpose.

In practice, the glass parts, that is the exhaust tubulation 59 and tubing sections 24a and 25a, are cut and cleaned in accordance with any suitable process known in the art. For instance, the glass parts may be cut on a wet Carborundum wheel and placed in a beaker of water immediately after cutting, and upon removing these parts from the water, the cut surfaces may be scrubbed with a brush before drying to prevent Carborundum powder from adhering to the glass.

The metal parts, that is the anode 28 and grid-ring 52, are initially treated by subjecting them to a degreasing process. The degreasing process

is preferably accomplished by submerging and agitating the metal parts in several carbon tetrachloride solutions successively, allowing sufficient time for the parts to drain after each submerging and agitating operation, and completely drying the parts after the last draining operation. As a practical expedient, the metal parts may be placed in a wire basket which may readily be transferred from one solution container to another, suspended and rotated therein to agitate the parts, and withdrawn from and hung over each container for drainage of the solution. It has been found that the metal parts will be degreased with sufficient thoroughness if the wire basket, with the parts therein, is dipped into three separate carbon tetrachloride solutions, rotated in each solution for about two or three minutes, drained after each dipping and, after the last draining, placed in a drier for about three minutes. The degreased metal parts are then fired at approximately 900° C. in an atmosphere of wet hydrogen for about thirty minutes and thereafter cooled for about five minutes. The degreased and fired metal parts are finally oxidized in air at approximately 900° C. for about three minutes.

Thus treated, the anode-grid-ring unit may be assembled by sealing the glass parts to the metal parts. This may readily be accomplished by arranging the parts on a rotary lathe in the relationship shown in Fig. 5 but with the adjacent surfaces of the anode flange 57, the tubing section 24a, the grid-ring 52 and the tubing section 25a in snug abutting engagement, and with the exhaust tubulation 59 supported in spaced relationship to the top of the anode. With the parts thus arranged, firing flames are directed, substantially as indicated by arrows A and B in Fig. 7, to simultaneously contact the points of engagement between the glass tubing section 24a and the anode 28, and the glass sections 24a and 25a and the grid-ring 52. The firing flames are maintained on these points for about two minutes or until the temperature of the glass and metal slowly rises to approximately 1000° C. or 1100° C. when seals, such as indicated at 60 in Fig. 7, begin to form. Thereafter, each seal is separately heated for about two minutes at the mentioned temperatures, blowing out the seal whenever necessary. In this manner strong hermetic seals are established between the metal parts and glass tubing sections.

When these seals 60 are established, the top surface of the anode 28 is heated to a temperature of approximately 1000° C., whereupon said surface and the confronting edge of the tubulation 59 are brought together and heated to said temperature by directing a firing flame substantially as indicated by the arrow C in Fig. 7. This heating is continued for about one to one and one-half minutes or until an effective strong hermetic seal, such as represented at 61 in Fig. 7, is obtained. This seal is blown out, if necessary, to prevent closing of the tubulation.

Immediately upon finishing the seals 60 and 61, the unit is subjected to a bushy annealing flame, allowing the temperature of the seals to drop to a dull red heat. The unit is then removed from the lathe and covered with asbestos powder, thus causing the seals to cool slowly and accordingly assuring proper setting of said seals.

The sealed anode-grid-ring unit is annealed preferably in an oven capable of operating at 500° C. and insulated to cool at a rate of 3° C. per minute. The unit is placed in the oven and the temperature is raised to approximately 500° C. This

temperature is maintained for about two hours after which the heat is turned off and the unit is left in the oven until the temperature drops below approximately 200° C.

After the anode-grid-ring unit has been subjected to the annealing process, said unit is finally cleaned to remove dirt and oxides from the parts. For that purpose, the following solutions are preferably used:

Solution I:

Boric acid	gm.	100
Distilled water	cc.	500
Hydrochloric acid	cc.	500

Solution II:

Distilled water	cc.	500
Hydrochloric acid	cc.	500
Nitric acid	cc.	500

Solution III:

Chromic acid	gm.	250
Sulfuric acid	cc.	80
Distilled water	cc.	1000

Solution IV:

Ammonium hydroxide	cc.	300
Distilled water	cc.	600

To clean the anode-grid-ring unit, solution I is heated to the boiling point. The unit is then immersed and constantly agitated in this boiling solution for about fifteen seconds. The unit is then removed from solution I and rinsed in running tap water. Thereafter, the unit is placed, for about three minutes, in solution II which is kept in a water jacket, while in use, to maintain said solution substantially at room temperature. When removed from solution II, the unit is again rinsed in running tap water and placed in solution III for about thirty seconds, after which the unit is removed, rinsed once more in running tap water and then placed in solution IV for about three minutes. Upon removal from solution IV, the unit is washed in running tap water for about two minutes and allowed to dry thoroughly. When dried the inside of the unit is polished, for instance, with steel wool.

Grid unit

Fig. 6 shows the several parts which form the grid unit 21. These parts include the grid cap 47, the grid support 48, the plurality of grid-wire elements 49 and grid reinforcing members 50. These parts are made of suitable metal, the grid cap and support being preferably made of nickel and the grid elements and reinforcing rods being made of tungsten. These parts are first degreased and hydrogen fired in the same manner as previously described in connection with the metal parts of the anode-grid-ring unit, excepting that the firing time may be cut down to ten minutes.

In assembling the grid unit, the grid support 48 and grid cap 47 are arranged and fixedly held in space aligned relation preferably on a welding mandrel. Tungsten wire sections forming the grid elements 49 may then be readily welded onto the grid cap and support which, for that purpose, are preferably provided with annular flanges as shown, in Fig. 6, at 47a and 48a respectively. In practice, the welding mandrel adapted to hold the grid cap and support, may conveniently be mounted for axial rotation and associated with graduated indexing means. In this manner the mandrel may be rotated in one division for each

welding operation, thus assuring the accurate location of the grid elements circumferentially of the cap and support to provide the "squirrel-cage" like grid as more clearly shown in Fig. 7. The reinforcing connector rods 50 are likewise readily welded at widely spaced points circumferentially of grid unit and in the plane of the grid elements 49.

The assembled grid unit is subjected to a final firing treatment at approximately 900° C. in an atmosphere of wet hydrogen for about ten minutes, to remove all the oxide traces which may have been deposited on the parts during the welding operation.

10 The finally treated grid unit may then be mounted in the finally treated anode-grid-ring unit to complete the anode-grid assembly section. This is preferably accomplished on a horizontal lathe, or equivalent, fitted with collet type chucks at both ends. The anode-grid-ring unit is placed in one chuck and a grid alignment mandrel is held and lined up in the opposite chuck. The grid unit is then placed on the end of the mandrel and brought in position (see Fig. 7) within the 15 anode-grid-ring unit so that the openings 54, in the flange 51 of the grid support 48, register with the screw-threaded apertures 55 in the grid-ring 52, and the body of the grid is properly aligned with the body of the anode. For that purpose, 20 the openings 54 are preferably made slightly larger than the threaded openings 55 so as to allow the grid-unit a certain amount of play for obtaining accurate and precise alignment between the effective surfaces of the grid and anode. With 25 proper alignment of the grid and anode, the screw-threaded elements 53 are passed through the openings 54 of the grid support and into engagement with the screw-threaded apertures 55 of the grid-ring, and are tightly driven home, 30 thus establishing a rigid connection between the grid and grid-ring to complete the anode-grid assembly section.

CATHODE ASSEMBLY SECTION

Base-connector unit

Fig. 8 illustrates the parts forming the base-connector unit. These parts include the base 32 and the tubular connector member 37 which are made of suitable metal alloy such as "Kovar." After these parts have been degreased in the manner already stated, they are assembled, as shown in Fig. 8, so that the tubular connector member 37 snugly fits into the re-entrant portion 31 of the base 32. The parts are then rigidly interconnected by brazing at the point indicated at 38. This is preferably accomplished by inserting a ring of copper wire at said point, standing the assembled unit in a tray with the exposed portion of the connector member extending upwardly, firing the unit in hydrogen for about two minutes at approximately 1150° C. and then allowing the unit to cool for about five minutes. Thereafter the brazed unit is oxidized in air at approximately 900° C. for about three minutes.

Cathode-base unit

Fig. 9 shows the parts which are connected to 70 the base connector unit to form the cathode-base unit. These parts include a ring of fusible material represented in broken lines at 35a, which is adapted to be rolled into a bead 35b for cooperation with a bead 35c on the heater rod 36 to form 75 the seal 35 (see Figs. 2 and 10), and a tubing sec-

tion 25b, which forms a portion of the envelope 25 (see Figs. 1 and 2). The heater rod is made of suitable metal alloy such as "Kovar," and the fusible ring, heater rod carried bead and tubing section are preferably made of glass such as "Corning-7052."

In providing the heater rod 36 with its bead 35c, said rod is first degreased as above stated and thereafter fired at approximately 900° C. in an atmosphere of wet hydrogen for about thirty minutes and then cooled for about five minutes. A small tubular glass section is cut, cleaned and dried in the manner previously stated. This cut, cleaned and dried glass section may then be slipped in position onto the heater rod which is supported on a rotary lathe. Firing flames are then directed onto the rod and glass to heat the same to approximately 1000° or 1100° C. for about two minutes or until the glass becomes sealed to the rod as shown in Fig. 9.

In forming the bead 35b, the glass ring 35a shown in broken lines in Fig. 9, is cut, cleaned and dried in the same manner as above specified, and is placed over the reduced neck section 34 of the base re-entrant portion 31 which is supported in a rotary lathe. Firing flames are then directed onto the glass, and, as the glass begins to melt, the top part thereof is folded inwardly of said neck section. The temperature is then increased to approximately 1000° C. or 1100° C. and maintained at that degree for about two and one-half or three minutes, or until proper sealing on the inside as well as on the outside of the neck section 34 is obtained.

In forming the seal 35 (Figs. 2 and 10), the beaded heater rod 36 is assembled with the beaded cathode-base unit as shown in Fig. 9 so that the beads 35b and 35c contact each other. The contacting glass beads are then melted and fused by directing firing flames thereon for about two and one-half to three minutes or until said seal 35 is obtained.

In sealing the glass tubing 25b to the base 32, said tubing and base, with the heater rod sealed thereon, are arranged on a rotary lathe in the relationship shown in Fig. 9 but with their adjacent surfaces in snug abutting engagement. Firing flames are then directed to slowly raise the temperature of the glass and metal to approximately 1000° C. or 1100° C., this temperature being maintained for about two and one-half to three minutes or until there is obtained a seal such as is shown at 63 in Fig. 10, thus completing the cathode-base unit.

The completed cathode-base unit is first annealed and cleaned in the same manner specified above for the annealing and cleaning of the anode-grid-ring unit, and is then silver plated. The silver plating is preferably done with the following equipment and solutions:

Power supply:

Direct current _____ volts 6

Silver anode:

Pure silver _____ percent 99

Dip solution:

Potassium cyanide (KCN) _____ grams per liter 70

Strike solution:

Silver cyanide (AgCN) _____ grams per liter 6

Potassium cyanide (KCN) _____ do 70

Specific gravity _____ 1.040

pH _____ 10.65 75

Plating solution:

Silver cyanide (AgCN)

grams per liter 86

Potassium cyanide (KCN) _____ do 52

Potassium carbonate (K₂CO₃) _____ do 38

Carbon disulfide (CS₂) _____ cc./l 0.20

Specific gravity _____ 1.060

pH _____ 10.9

10 The solutions are prepared by dissolving the potassium cyanide, the silver cyanide and the potassium carbonate. The carbon disulfide is added to a small quantity, say 100 cc., of the plating bath and allowed to stand for five days with occasional mixing. The clear supernatant fluid is poured off and added to the bath as a brightener.

15 The plating process is preferably carried out in accordance with the following procedure:

- 20 A. The solutions above identified are used at a temperature of approximately 20° C.; and,
- B. The unit is treated in the following order:
1. Place unit in dip solution for approximately thirty seconds;
  2. Place unit in strike solution for thirty to sixty seconds using 6 volts and a current density of 2.0 amps. per sq. decimeter. Time may vary but should be the shortest time possible to cover the metal completely;
  3. Place unit in plating solution. Time may vary with the thickness desired. In practice two and one-half minutes using 2 volts and a current density of 1.0 amps. per sq. decimeter has been found satisfactory;
  4. Place unit in stagnant cold distilled water bath from which the silver can be reclaimed;
  5. Place unit in warm running tap water;
  6. Place unit in distilled water;
  7. Dry unit immediately in acetone and air; and
  8. Polish unit on hard cloth wheel.

Cathode-base-heater unit

Fig. 10 shows the parts forming the heat-baffle structure and cathode-heater, and the mode of mounting the same on the plated cathode-base unit.

55 The disks 42 and rods 43 and 46 of the baffle structure are made of suitable metal, the disks being preferably made of nickel and the rods being preferably made of "Kovar." These parts are first degreased and hydrogen fired in the manner previously stated. The disks 42 and rods 43 are then joined as shown, for instance, in Fig. 10, by welding said rods to the inside surface of the disk flanges, making sure that the apertures 44 in the disks are aligned. The ceramic inserts 45 may then be associated with the disks of the baffle unit and slipped in position onto the heater rod 36, whereupon the spacer rod 65 may be welded on said heater rod between the ceramic inserts to hold the baffle unit in place.

60 The cathode-heater is preferably made of tungsten wire closely wound to form the coil-type heater 39. One end of this heater is provided with a tightly wound portion 64 while the other end of said heater is provided with a depending portion 65 to which the heater connecting extension 40 is affixed, as by welding. The cathode-heater thus constructed, is preferably first cleaned and hydrogen fired in the manner above

11

stated, and then coated to a diameter increase of .008" to .010" with the following solution:

Alundum "38-500" (Norton Company) grams... 500
Lacquer "RL-1" (Raffi and Swanson) milliliters... 500

In preparing this solution, the Alundum is baked, prior to mixing, for at least 12 hours at 200° C. in an oven with forced air circulation, the Alundum and lacquer are then milled in a quart porcelain jar with 1 1/2 lbs. of 3/4" to 1 1/2" flint pebbles for 48 hours at 96 R. P. M.

The coated cathode-heater may then be attached to the heater rod 36. This is readily accomplished by passing the connecting extension 40 through the baffle disk apertures 44, and by snugly and rigidly engaging the tightly wound portion 64 of said heater to the end of the heater rod, after which the free end portion 66 of said section may be securely welded to the reduced section 34 of the base re-entrant portion 31 as indicated at 41 (see Fig. 11). It is to be noted that the mentioned end portion of the connecting extension 40 is provided with an offset section 67 to clear the seal 35 at said reduced section 34.

Cathode-insulator unit

Fig. 11 shows the construction of the cathode-insulator unit and its association with the cathode-base-heater unit. The cathode-insulator unit comprises the cap-shaped cathode 26 and the tubular thermal insulator 30 both of which are preferably made of nickel. The cathode and thermal insulator are first degreased and hydrogen fired in the manner already stated, and then united bylapping a portion of the insulator over a portion of the cathode at the open end thereof. These over-lapping portions are welded thus joining the cathode and thermal insulator to form a rigid unit which may then be slipped in position, as shown, for example, in Fig. 11, onto the re-entrant portion 31 of the cathode base 32 and into engagement with the shoulder 33 thereon, to be fixedly secured on said re-entrant portion, as by welding. In constructing and mounting the cathode-insulator unit in manner above described, it will be appreciated that the cathode is properly and effectively supported without the necessity of employing wire frames or dielectric supporters.

When the cathode-insulator unit and the cathode-base-heater unit have been assembled, the outer circumferential surface of the cathode is coated, as at 29, with a suitable solution to assist in the emission of electrons. The following solution has been found most satisfactory:

Radio Mixture #1 (J. T. Baker Chemical Co.)	grams	300
Radio Mixture #2 (J. T. Baker Chemical Co.)	grams	1200
Lacquer "RL-1" (Raffi and Swanson)	milliliters	2150

In preparing this solution for use, the "Radio Mixture #1" and "Radio Mixture #2" are baked before mixing, for at least 12 hours at 200° C. in an oven with forced air circulation. Then, these mixtures and the lacquer are ball milled in a five quart porcelain jar with 5 lbs. of 3/4" to 1 1/2" flint pebbles for 48 hours at 64 R. P. M.

The cathode surface is coated with this solution so that the density is .95-1.05 mg./sq. cm., the coating weight is 20-28 mg., and the diameter increase is .008-.010".

12

FINAL TUBE ASSEMBLY

In accordance with the present invention, the tube is finished by effecting a final glass-to-glass seal between the anode-grid assembly section and the cathode assembly section. This may be readily accomplished on a rotary lathe which is fitted out with collet type chucks on both ends, and which is provided with means for injecting nitrogen while sealing, and with a microprojector for aligning the sections on the lathe.

aligning the sections of the lathe.

15 The anode-grid assembly section is aligned and held in the fixed end of the lathe, and the cathode assembly section is placed and held in the movable end of the lathe. With the lathe rotating, the coated portion of the cathode is adjusted with the aid of the microprojector until no lateral or angular movement is noticeable on the projection screen, thus indicating the proper alignment.

20 25 30 35 40 45 50 55 60 65 70 75 80 85 90 95 100

25 The cathode extends longitudinally within and in accurate concentric relation with the grid and anode, the confronting edges of the glass tubing sections 25a and 25b abutting each other. The abutting glass tubing sections 25a and 25b may then be sealed and fused together, as represented at 68 in Fig. 2, blowing out where necessary to form the unitary envelope 25. It is particularly pointed out that since the final seal is made glass-to-glass, the metal parts are not detrimentally affected by the heat applied to effect such seal, and therefore the danger of disaligning said parts is eliminated.

Following the final sealing operation, the air within the tube may be exhausted in the customary manner through an aperture 69 in the top of the cathode 26, through the aperture 58 in the top of the anode 28, and through the tubulation 59 which, after exhaust of the tube, may be tipped off as represented at 59a in Figs. 1 and 2, to hermetically seal the tube thus completing the same.

45 The completed tube may then be thoroughly cleaned, polished and the external metal parts silver plated in accordance with the processes hereinbefore specified.

50 While, in the preceding description, the treatment of the several parts, forming the individual units and sections, have been described in the order herein chosen, it is to be understood that, in practice, all the parts which are to be subjected to the same treatment, may be processed 55 at one time, regardless of the unit or section in which these parts are to be included. For example, all the metal parts may be initially degreased and fired, and all the glass parts may be initially cut, cleaned and dried. Thereafter, 60 these metal and glass parts may be segregated and stored, to be subsequently selected for assembling the units and sections. Likewise, the units as well as the sections, may be made in quantities, and treated in one phase of operation, to be 65 thereafter selected for final assembly in the manufacture of the tubes.

TUBE COOLING

70 The power output of the tube, as above described, may be enhanced greatly by cooling it in a positive manner. For that reason, in the construction of the tube according to the present invention, provision is made for intimate association with either a special air-cooled device 70

(Fig. 12) or a special water-cooled device 71 (Fig. 14).

The air-cooled device 70, as shown in Fig. 12, comprises a substantially cylindrical body portion 12 of relatively heavy metal construction. The body portion is provided with laterally projecting fins 73 and with a shank 74 terminating with a reduced end extension 75 adapted, as illustrated in Fig. 13, to fit snugly into the inset well portion 56 of the anode 28. Slots 76 (Fig. 12) are cut through the thickness of the shank 74 and end extension 75, and are extended longitudinally thereof so that said shank and extension may tightly grip the outer circumferential surface of the anode 28 (see Fig. 13) upon tightening a clamp 77 surrounding said shank.

The water-cooled device 71, as shown in Fig. 14, comprises an inner cylinder 78 and an outer cylinder 79 disposed concentrically with respect to each other and having a closed end 80 (Fig. 15) to provide separated chambers 81 and 82, as can be more clearly seen in said Fig. 15. The device 71 is adapted to be placed over the anode 28 and fixedly secured thereto for instance by soldering, as indicated at 83 (Fig. 15) so that the body of said anode lies within the chamber 81 in concentric relation with the inner cylinder 78 but slightly spaced therefrom, said inner cylinder then lying approximately midway of the width of the anode well portion 56. In this manner the anode and cylinders cooperate to constitute a restricted pathway for the circulation of water between the chambers 81 and 82. A water inlet 84 discharges into the chamber 81, and a water outlet 85 discharges from the chamber 82. Thus in using the water-cooled device 71, water admitted through the inlet 84 in the chamber 81, flows in contact with the anode 28, through the restricted pathway, into the chamber 82, and out the outlet 85, as represented by the arrows in Fig. 15. Because of the restricted pathway in the immediate vicinity of the anode, it will be appreciated that the water, at that point, circulates under greatly increased velocity which is most effective in carrying the heat away from the anode.

From the foregoing description, it will appear that the present invention materially simplifies the manufacture of ultra-high frequency vacuum tubes which are capable of relatively high power output at continuous or substantially continuous operation. Moreover the invention provides a tube, of the kind specified, with numerous characteristic structural and electrical features which make such a tube most dependable in its operation.

It is particularly pointed out that this tube is so constructed that the mounting of the electrode elements does not require the use of dielectric supports. This avoids losses at high frequencies that would take place in the dielectric material used as conventional supports for the electrodes.

Whereas the preferred specific embodiment of the tube and the preferred specific mode of handling and processing the parts thereof have been herein shown and described, it is to be understood that changes in the construction and treatment of the tube or any of the parts forming the same, may be made within the scope of the subjoined claims.

We claim:

1. A high-frequency vacuum tube of the triode type comprising coaxially and concentrically mounted cathode, grid and anode structures with the anode and grid co-axially surrounding the cathode; said cathode structure including a base

member providing a cathode connection and having a cylindrical re-entrant portion, a tubular thermal insulator having one end portion connected with said re-entrant portion to extend coaxially therefrom, an inverted cup-shaped cathode element connected with the free end portion of said insulator and supported thereby in coaxial alignment therewith, cathode heating means carried by said re-entrant portion of the base member and disposed concentrically within said cathode element, and a heat insulating baffle substantially closing off the otherwise open end of said cup-shaped cathode element.

2. A high-frequency vacuum tube of the triode type comprising coaxially and concentrically mounted cathode, grid and anode structures; said grid structure including a pair of annular supports spaced axially from each other, a plurality of grid wire elements spanning the space between said supports and fixedly connected thereto and a separate series of rigid tie rods rigidly mounting said supports in spaced parallelism, one of said supports having an outwardly flaring skirt terminating with an annular lateral flange, and a grid ring providing a grid connection and disposed for direct rigid engagement with said flange to fixedly support the grid elements in parallel relation to the axis of the cathode and in close proximity to the electron emitting surface of the latter.

3. A high-frequency vacuum tube of the externally exposed anode type comprising co-axially and concentrically mounted cathode, grid and anode structures; said cathode structure including a base member providing a cathode connection and having a cylindrical re-entrant portion, a tubular thermal insulator having one end portion connected to said re-entrant portion to extend coaxially therefrom, an inverted cup-shaped cathode element connected to the free end portion of said insulator and supported thereby in coaxial alignment therewith, a heat baffle member substantially closing off the otherwise open end of said cup-shaped cathode element, cathode heating means carried by said re-entrant portion of the base member and disposed concentrically within said cathode element; said grid structure including a grid body and a grid ring providing a grid connection and disposed for direct engagement with said grid body to rigidly support the same coaxially and concentrically of the cathode; and said anode structure including a cylindrical body having an annular well portion terminating with an annular lateral flange portion forming an anode connection, said well portion providing the anode body with a substantial portion closer to the grid ring than is the anode lateral flange to make effective the portion of the grid adjacent thereto.

4. A high-frequency vacuum tube of the externally exposed anode type comprising coaxially and concentrically mounted cathode, grid and anode structures; said grid structure including a pair of annular supports spaced axially from each other, a plurality of grid wire elements spanning the space between said supports and fixedly connected thereto, another plurality of rigid tie rods separate from said grid wires rigidly mounting said annular supports in spaced parallelism, one of said supports having an outwardly flaring skirt terminating with an annular lateral flange, a grid ring providing a grid connection and disposed for direct engagement with said flange and rigidly mounting the grid elements in parallel relation to the axis of the cathode and in close proximity to the electron emitting surface of the latter;

15

said anode structure including a cylindrical body having an annular well portion terminating with an annular lateral flange portion forming an anode connection, said well portion providing the anode body with a substantial portion closer to the grid ring than is the anode lateral flange to make effective the portion of the grid adjacent thereto while providing adequate spacing between the grid and anode connections.

5. A high-frequency vacuum tube of the triode type comprising coaxially and concentrically mounted cathode, grid and anode structures; said cathode structure including a base member providing a cathode connection and having a cylindrical re-entrant portion, a tubular thermal insulator having one end portion connected with said re-entrant portion to extend coaxially therefrom, an inverted cup-shaped cathode element connected with the free end portion of said insulator and supported thereby in coaxial alignment therewith, and a heat baffle substantially closing off the otherwise open end of said cup-shaped cathode element and cathode heating means carried by said re-entrant portion of the base member and disposed concentrically within said cathode element; said grid structure including a pair of annular supports spaced axially from each other, a plurality of grid wire elements spanning the space between said supports and fixedly connected thereto, a separate plurality of tie rods rigidly mounting said supports in spaced parallelism, one of said supports having an outwardly flaring skirt terminating with an annular lateral flange, a grid ring providing a grid connection and disposed for direct engagement with said flange and rigidly mounting the grid elements in parallel relation to the axis of the cathode and in close proximity to the electron emitting surface of the latter; and said anode structure including a cylindrical body having an annular well portion

terminating with an annular lateral flange portion forming an anode connection, said well portion providing the anode body with a substantial portion closer to the grid ring than is the anode lateral flange to make effective the portion of the grid adjacent thereto while providing adequate spacing between the grid and anode connections.

6. A grid unit for high frequency vacuum tubes comprising, a pair of annular members, a plurality of rigid tie rods fastened to said members for maintaining them in fixed parallelism, a plurality of grid wires fastened at their ends respectively to said annular members to form therewith a squirrel cage construction, one of said annular members terminating in a downwardly and outwardly extending flared skirt having a flat marginal flange for attaching the grid unit to a suitable support.

7. A grid unit according to claim 6 in which said grid wires are bowed inwardly at opposite ends adjacent their regions of connections to said annular members.
